UNITED STATES PATENT OFFICE.

WALLACE W. BOOTH, OF BROOKLYN, NEW YORK.

FURNACE BRIDGE WALL.

Application filed December 16, 1921. Serial No. 522,768.

To all whom it may concern:

Be it known that I, WALLACE W. BOOTH, a citizen of the United States, and a resident of the borough of Brooklyn, county of 5 Kings, city and State of New York, have invented certain new and useful Improvements in Furnace Bridge Walls, of which the following is a specification.

My improvements relate to the so-called 10 hollow sectional type of fire bridges for furnaces, in and through which air from the ash pit is heated and fed to the fire box; and are designed to attain simplicity of construction; a maximum of internal heating 15 surface and positive tortuous air contact therewith; perfect combustion of the fuel constituents and the elimination of smoke; stability of section installation combined with facile removal and substitution; and 20 other incidental advantages hereinafter mentioned;—the invention consisting essentially in the specific structural arrangement of parts described and claimed, and distinctive features being the copulative and locking means, and the formation of baffle air 25 passages, substantially in the manner and for the purposes hereinafter fully set forth.

In the accompanying drawings,

Fig. 1, is a transverse section of a furnace 30 flue showing my improved bridge wall construction in front elevation;

Fig. 2, is a front view, on a larger scale, of the two end sections, and two of the intermediate sections, of the upper portion of 35 the bridge wall structure;

Fig. 3, is a transverse section of the bridge wall structure, taken upon plane of line 3—3, Fig. 1, but upon a larger scale;

Fig. 4, is a transverse section of my bridge 40 wall construction like unto that shown in Fig. 3, showing a bridge top section positioned to resist displacement by frontal pressure;

Fig. 5, is a like section showing the function 45 of the interlocking parts in preventing top section displacement by rear pressure thereon;

Fig. 6, is a front view, on a reduced scale, 50 of the basic bridge supporting partition plate, with one half of the bridge shelf in position thereon;

Fig. 7, is a sectional detail of the other 55 half of the bridge shelf, taken on plane of line 7—7 Fig. 9;

Fig. 8, is a horizontal section of a portion

of a corrugated furnace tube, showing a plan of the bridge shelf, the bridge top sections being omitted;

Fig. 9, is a transverse section of the bridge shelf, taken upon plane of line 9—9, Fig. 8; 60

Fig. 10, is a side elevation of one of the medial bridge top sections;

Fig. 11, is a front elevation thereof;

Fig. 12, is a section of two adjoining medial top bridge sections, taken upon the 65 planes of line 12—12, Fig. 10;

Fig. 13, is a sectional detail of the rear portions of adjacent bridge top sections, showing a modification in the overlap.

In the drawings F, is used to designate 70 a portion of a corrugated cylindrical furnace flue of well known form and construction, in the lower part of which the bridge wall is installed, said bridge wall consisting essentially of a basic foundation plate B, 75 which also partitions off the ash pit A, from the rear portion of the furnace flue F, as shown more particularly in Fig. 3, of the drawings, and in this respect functions also as a baffle; of the bridge shelf S, secured 80 to said basic supporting partition B; and of a series of bridge top sections C, C, demountably positioned on said bracket shelf S.

The basic partition plate B, is formed with front and rear feet flanges b, b, which 85 conform to the corrugated bottom of the flue F, as shown in Fig. 3, and also with frontal bracket lugs b', b', for the support of the bridge shelf S.

The latter may be made in one or more 90 divisions, as may be found most expedient in practical application. As shown in the drawings it is made of two divisional portions, the conjunctive cross ribs s, s, of which are bolted together, as indicated in Figs. 3 95 and 8. The shelf S, considered in a unitary sense, is also rigidly attached to the upper part of the basic partition B, as by bolts shown in Figs. 3 to 5 inclusive. The forward edge of said shelf is formed with a flanged 100 ledge s^x for the support of the rear ends of the grate bars (g) as indicated in Fig. 3, in a manner well known in the prior state of the art. The top of the shelf is formed with parallel bearing surfaces s', s², constituting rests for the demountable top sections C, C, of the fire bridge,—these bearing surfaces s', s², extending in a common horizontal plane, except that the rear rest s², is 105 slotted longitudinally (as shown at s²¹, Fig. 110

8, particularly) and is furthermore provided with a longitudinal shoulder s^{22} , for contactual engagement, under certain conditions with the heels of the bridge top sections C, C, as hereinafter set forth. Between the front bearing surface s' , and the rear bearing surface s^2 , thereof, the shelf S, is open for the passage of air from the ash pit A, except where the cross ribs s, s , occur, which said cross ribs s, s , rigidly connect the longitudinal members of the shelf S, and, as will be understood more particularly by reference to Fig. 8, taken in conjunction with Figs. 3, 4, 5 and 9,—the upper edge of the basic partition B, being formed with recesses b^2, b^2 , for the accommodation of the cross ribs s, s , as indicated in Fig. 6. It may be noted, in this connection, that the shelf S, while rigidly attached to the basic partition plate B, is integral in structure, and has no projection above its bearing surfaces s', s^2 , other than the rear shoulder s^{22} . Thus the bridge top sections C, C, are installed "on the flat" in so far as the shelf S, is concerned, and are not suspended nor dependent upon rear plate or wall support of any kind, which is a great practical advantage as compared with the prior state of the art, because of simplicity of structure and facility of manipulation.

All the demountable bridge top sections are of arcuate configuration, their frontal surfaces being convexly curvilinear, so as to afford an upwardly receding barrier for the support of the fuel at the rear of the grate bars. They are all alike in this respect, even the end sections C', C' which are shaped to conform to the adjacent inner side walls of the furnace F. Each intermediate section C, is formed with a medial web c , of less thickness than the face flange c' , thus creating recesses c^2 , at the rear of said face flanges c' , and these recesses c^2 , are sub-divided by a plurality of lateral baffle flanges c^3, c^3 , on opposite sides of the web c , the baffle flanges c^3 , on one side of the web c , intervening in position as related to those on the under side thereof, so that when the sections C, C, are mounted side by side on the shelf S, tortuous passages are created between adjoining sections, as shown more particularly in Fig. 12, of the drawings,—and as indicated by arrows in said figure. Communicating with these intermediate recesses c^2, c^2 , thus formed, are the assembly air ejector passages 1, 2, 3 and 4, formed by the coincidental grooves in both edges of the face flanges c' , and by means of which the hot air from the ash pit A, is introduced into the incandescent fuel banked up against the series of bridge top sections C, C, to promote and perfect combustion prior to the escape of the gaseous products thereof over and beyond the fire bridge.

The lower extremity of the rear member or leg c^4 , of each top section C, is formed with a foot c^5 , broader than the width of the slot s^{21} , in the shelf S, so as to rest and bear upon the edges of said slot s^{21} , said foot c^5 , being however provided with a toe c^6 , adapted to project into said shelf slot s^{21} , as shown in Figs. 3, 4 and 5. This interlocking of the leg c^4 , of each top section with the shelf S, is provided for the purpose of preventing displacement of the section C, during use by reason of undue frontal or rear pressure, as by push or pull of a grate rake carelessly or unskillfully handled. Thus, if the pressure or blow is against the face of the section C, the latter may be forced back until the foot c^5 , bears against the shoulder s^{22} , at the rear of the shelf S, as shown in Fig. 4, but can be forced backward no further; whereas a pull exerted against the rear member or leg c^4 , of the section C, will be counteracted by the engagement of the toe c^6 , with the rear wall of the slot s^{21} , as illustrated in Fig. 5, thereby obviating displacement.

In order to prevent the air from the ash pit from passing direct to and through the upper ejector passages 1, 2, and 3, and to insure its passage thereto through the tortuous passages created by the baffle flanges c^3, c^3 , as hereinbefore stated, I form each web c , with inclined flanges c^7 , extending from the upper part of the rear member or leg c^4 , of the section to below the lower baffle flanges c^3 , (see particularly Fig. 10); said inclined flanges c^7 , performing the additional function of acting as shields to protect the slot s^{21} , and the aforesaid interlocking means, from clogging by ash descending through the air passages 1, 2 and 3.

The continuity of the slot s^{21} , admits of the lateral adjustment of the bridge top sections C, as related to each other, and facilitates their individual and collective installation or removal and replacement, as they are free to be raised or lowered individually in a vertical direction.

In order to practically seal the joints between adjoining leg members c^4 , of the sections C, without impeding this freedom of individual vertical movement of the sections, I form said leg members c^4 , with overlap side flanges c^{41} , which close the lines of juncture, as indicated in Figs. 12 and 13, the latter showing a modification of structure in this respect as compared with Fig. 12.

The tortuous air passages created by the baffle flanges c^3 , on and between the webs of the bridge top sections, as above set forth, not only increase the heating capacity of the said sections by reason of augmented area of contactual surface for the air drawn from the ash pit, thereby practically super-

- heating said air and rendering its constituents highly nascent before injection into and through the fuel on the continuous front of the said bridge top sections, so as to promote the complete reduction of the oxidizable products of combustion before they pass the bridge wall, thus eliminating smoke, and avoiding loss of heat units, but said deflectors c^3 , also tend to prevent the overheating of the sections for a like reason,—i. e., they increase heat diffusion. Furthermore, they reinforce and stiffen the webs c , against any tendency to warp when subjected to a high degree of heat.
- 15 What I claim as my invention and desire to secure by Letters Patent is,
- A furnace bridge wall of the character designated, comprising a base partition, a shelf mounted thereon and formed with parallel bearing surfaces with air passages therebetween, and with a frontal ledge for the support of the rear ends of the grate
- bars, said shelf being also formed with a flangeless longitudinal rear lock slot open and of uniform width from one end of the shelf to the other, and with a back rest parallel thereto, and a plurality of independently demountable bridge top sections having overlapping vertical side flanges, and with face flanges having coincidental edge recesses, each section having a central web of less thickness than the width of its face flange, with baffle flanges on each side of said web, and deflector flanges therebelow, each section having a rear leg member formed with heel shoulders contacting with said shelf, and with a toe extending through said lock slot in said shelf, substantially in the manner and for the purpose set forth.

WALLACE W. BOOTH.
